UNITED STATES PATENT OFFICE.

CHARLES BOOZ, OF BUFFALO, NEW YORK, ASSIGNOR, BY MESNE ASSIGNMENTS, TO GEORGE K. BIRGE, OF SAME PLACE.

DESIGN FOR WALL-PAPER.

SPECIFICATION forming part of Design No. 24,811, dated October 29, 1895.

Application filed September 27, 1895. Serial No. 563,926. Term of patent 3½ years.

To all whom it may concern:

Be it known that I, CHARLES BOOZ, a citizen of the United States, residing at Buffalo, in the county of Erie and State of New York, 5 have invented and produced a new and original Design for Wall-Paper, of which the following is a specification, reference being had to the accompanying drawing, showing a part thereof.

10 The design consists of a large ornamental vase-like figure filled with flowers and leaves and having ornamental scrolls springing from the base of said figure with sprays of flowers and leaves attached to said scrolls, forming 15 ornamental panels inclosing the vase-like figure with the flowers and leaves in the center, as represented in the accompanying drawing.

The border of the design is formed of a similar large ornamental vase like figure filled with flowers and leaves and ornamental scrolls 20 springing from the base of said figure, as shown in the drawing.

What I claim is—

1. The design for wall-paper herein shown and described. 25
2. In the design for wall-paper, the border herein shown and described.

Witness my hand this 24th day of September, 1895.

CHARLES BOOZ.
